UNITED STATES PATENT OFFICE.

AARON M. WEBER, OF NEW YORK, N. Y.

STIFFENING-STRIP FOR GARMENT-WAISTS, CORSETS, &c.

SPECIFICATION forming part of Letters Patent No. 715,187, dated December 2, 1902.

Application filed March 5, 1902. Serial No. 96,791. (No model.)

To all whom it may concern:

Be it known that I, AARON M. WEBER, a citizen of the United States, and a resident of New York city, county of New York, and 5 State of New York, have invented certain new and useful Improvements in Substitutes for Whalebone Stiffening-Strips, of which the following is a specification, reference being had to the accompanying drawings, forming a part 10 thereof, in which similar letters of reference indicate corresponding parts.

My invention relates to a new article of manufacture which may be employed as stiffening strips or stays in women's dresses or as 15 binding-strips wherever stiffness may be desired, and is in the nature of an improvement over substitutes for whalebone and steel stays heretofore made.

My invention consists of a flat strip cut from 20 a ratan, switch, or reed which I reinforce by means of stiff wires suitably held against the reed and covered by a woven fabric, as will be hereinafter fully described.

Heretofore stiffening-strips have been made 25 up of various substances, principally the quill portions of feathers, which are expensive to manufacture.

My invention is intended to provide a stiffening-strip stronger and cheaper than any 30 of the stiffening-strips heretofore made.

Referring to the drawings, Figure 1 shows a portion of the flat reed or ratan strip. Fig. 2 is a sectional view of same. Fig. 3 is a view showing the reed with reinforcing-wire attached thereto. Fig. 4 is a section view of 35 same. Fig. 5 is a view showing a portion covered with the woven-web covering; and Fig. 6 is an end view of the reed, showing the wires at the edges of the reed.

40 In practice I employ a flat strip of ratan or a reed *a* and fasten (preferably by means of a woven thread *b*) longitudinally along it on both sides one or more wires *c*, and over the whole I weave a covering *d*.

45 In the drawings I have shown only one wire fastened along each side of the strip *a*; but

it is obvious that two or more wires may be fastened on each side, according to the stiffness required, or the wires may be run along the edge of the strip of ratan, as shown in 50 Fig. 6.

Instead of the reed I may use any pliable strip and reinforce same with the wires. I do not, therefore, wish to be understood as limiting myself entirely to the reed described. 55

Instead of fastening the wires by means of a continuous woven thread I may fasten them at intervals by threads, bands, or other suitable means, or I may dispense with a fastening for the wires and weave the covering directly over the reed and wires. 60

It will be noticed I provide the resilient bracing-wires on opposite surfaces of the frangible strip, and it will be understood that by "surfaces" I mean the sides or the edges 65 of the strip, as the case may be.

Having thus described my invention, what I claim as new, and desire to secure by Letters Patent, is—

1. A stay, comprising a flat strip of ratan 70 having upon each edge thereof a wire, the whole inclosed in a casing, substantially as described.

2. A stay comprising a flat strip of ratan, having upon each edge thereof a wire, a binding thread or cord holding the said wire and the whole inclosed in a casing substantially 75 as described.

3. As an improved article of manufacture the stiffening-stay comprising a frangible 80 foundation-strip of wood, resilient embracing-wires extending along the opposite surfaces of said strip and a casing inclosing said strip and wires substantially as set forth.

In testimony that I claim the foregoing as 85 my invention I have signed my name, in presence of two witnesses, this 20th day of February, 1902.

AARON M. WEBER.
